CLAIM

The ornamental design for a napkin holder, as shown and described.

DESCRIPTION

FIG. 1 is a perspective view of a napkin holder showing our new design;

FIG. 2 is a side elevational view thereof;

FIG. 3 is a front elevational view thereof; and,

FIG. 4 is a top plan view thereof.

The portion of the base perimeter that is shown broken away indicates that the space between the two ends may vary. The cross-hatching does not indicate a type of material, but only identifies the section break.
